US00D845960S

(12) **United States Design Patent** (10) **Patent No.:** **US D845,960 S**
(45) **Date of Patent:** **** Apr. 16, 2019**

(54) **ELECTRONIC DEVICE ATTACHMENT
PORTION OF A DASHBOARD VENT MOUNT
FOR AN ELECTRONIC DEVICE**

(71) Applicant: **Kenu, Inc.**, San Francisco, CA (US)

(72) Inventors: **David E. Yao**, San Francisco, CA (US);
Leonard John Duran, Mill Valley, CA (US); **Gregory D. Caneer**, Oakland, CA (US); **Kenneth Y. Minn**, San Francisco, CA (US)

(73) Assignee: **KENU, INC.**, San Francisco, CA (US)

(**) Term: **15 Years**

(21) Appl. No.: **29/663,047**

(22) Filed: **Sep. 11, 2018**

Related U.S. Application Data

(62) Division of application No. 29/607,125, filed on Jun. 9, 2017, now Pat. No. Des. 831,660.

CLAIM

The ornamental design for an electronic device attachment portion of a dashboard vent mount for an electronic device, as shown and described.

DESCRIPTION

FIG. 1 is a rear perspective view of an electronic device attachment portion of a dashboard vent mount for an electronic device;

FIG. 2 is a front perspective view of the electronic device attachment portion of the dashboard vent mount for an electronic device;

FIG. 3 is a front elevational view of the electronic device attachment portion of the dashboard vent mount for an electronic device;

FIG. 4 is a rear elevational view of the electronic device attachment portion of the dashboard vent mount for an electronic device;

FIG. 5 is a top plan view of the electronic device attachment portion of the dashboard vent mount for an electronic device;

FIG. 6 is a bottom plan view of the electronic device attachment portion of the dashboard vent mount for an electronic device;

FIG. 7 is a right elevational view of the electronic device attachment portion of the dashboard vent mount for an electronic device; and,

FIG. 8 is a left elevational view of the electronic device attachment portion of the dashboard vent mount for an electronic device.
